METHOD AND APPARATUS COMPRISING A SANITARY PROTECTIVE MEANS FOR BEDS
AND THE LIKE

Application filed July 15, 1930. Serial No. 468,100.

Our invention embraces a new and basic principle in a device adapted for attachment to the ends of beds or similar structures as a protective means therefore.

5 The primary object of our device is the provision of a sanitary cover means whereby the front surface area of the bed head board is protected against contact with the head or hands of the occupant; this being especially 10 desirable in view of the modern and rapidly increasing tendency of furniture manufacturers to incorporate fanciful designs and cushioning effects of an overstuffed nature in connection with, and/or in substitution of 15 the paneling of the bed end, and the equally increasing tendency of the public to grease the hair and apply scalp remedies upon retiring.

Another object of our device is the provision of a sanitary shield which may readily be placed out of the way when the bed is not occupied, and which can be replaced daily if desired, and at a minimum of expense, for example, in hotel and club use where the 20 rooms are occupied by different persons, practically every night. It thus not only provides an absolutely clean, fresh and sanitary surface against which the head of the occupant of the bed may come in contact when 25 the device is attached to the head board, but also serves as a protecting cover means for either the head board or the foot board when thereto attached. This is of material advantage, especially when the board combines paneling of the overstuffed variety, in affording a cover means to guard against 30 soiling and damage.

35 Simplicity in its use and attachment, new and novel in its basic features, neatness, and few parts of light but durable construction; combine to make this invention of practical utility.

40 We attain these objects by the herein specifically described device illustrated in the accompanying drawings, in which:—

45 Figures 1 and 2 are respectively, views showing our invention in position for use, 1 indicating it on a straight end bed, 2 on a shaped or formed end bed, the foot end in each view being broken away. Figure 3 is a fragmentary back view of Fig. 1 showing our invention rolled up and collapsed. Figure 4 is a similar view showing the invention applied to the shaped or formed bed as indicated in Fig. 2. Figure 5 is an enlarged 50 fragmentary view partly in section showing the detail of the roll and other members of the invention. Figure 6 is an end view of Fig. 5. Figure 7 is a fragmentary side view of our invention of the form shown in Figs. 2 and 4; Figure 8 is a sectional view of Fig. 7. Figures 9 to 16 inclusive are modifications of our invention, Figure 9 being a fragmentary view of one form; Figure 10 a fragmentary sectional view thereof on line 10—10 55 Fig. 9; Figure 11 is a fragmentary view of another form; Figure 12 being a fragmentary sectional view thereof on line 12—12 Fig. 11; Figure 13 is a view similar to Figures 9 and 11 but embodying still another 60 form of our invention; Figure 14 being a sectional view of Fig. 13; Figure 15 is a sectional view of Fig. 9 showing the sanitary shield when not in use, and Figure 16 is a sectional view of Fig. 13 also showing the shield not 65 in use.

Similar numerals indicate like parts throughout the several views, the numeral 1 thus indicating our sanitary protecting shield disposed over the front paneling of 70 the head end of the bedstead and protecting the upholstered center pieces and surrounding panel from contact with the person of the occupant of the bed. 2 is a roller of similar form and construction to the spring roll 75 in common use for blinds and window shades, this being but one of the many means we have adapted for attaching the shield proper, other means comprising the customary means old in the drapery art as a sewed seam, sewed on rings, and curtain pin principle; and in addition to other means of 80 mechanical expediency, we may also use spring clip means whereby the material comprising the shield proper is secured to a rod 85 by a continuous or sectional spring tensional clip of the snap type. 3 indicates brackets secured to a mobile or movable bar 4, and a stationary bar 5 is secured to the bed A, bar 4 being secured to bar 5 in the type in 90 95 100

dicated in Figures 1 and 3 by single link members 6 and screws 17 and 18, while in the type indicated in Figures 2 and 4, bar 4 is secured to bar 5 by double link members 7 and 8, screws 27 and 28, and rivet 29, said bar and link members comprising a collapsible frame.

Roller 2 has trunnions 11 of rectangular shape which engage in sockets 12 in the brackets 3. The trunnion 11 extends through an end piece 15 into a socket or hole 9 in the body of roller 2, and secured to the inner end 10 of the trunnion 11 by a pin 14 is a spring 13 which has its outer end secured to roller 2 by means of a pin 15, a pawl 16 engaging the outer portion of the trunnion to retain it at any predetermined position in the same manner as a window shade is secured.

20 In the type of our invention shown in Figures 1 and 3, the stationary bar is held in position by bolts 19 in the ends of the bar 5, said bolts being slidably mounted in an aperture 20 and are forced outwardly under 25 tension of a spring 21, and secured against movement by a pin 22 in a slot 23.

In the type shown in Figures 2 and 4, due to the increased necessity of extending the movement of the roller 2 in a vertical direction, double links 7 and 8 are employed. 30 In Figure 7 one method of securing the shield to the roller is shown, said means comprising a spring band 32 movably secured to the roller by screws 33 and 34, and as is 35 apparent, screws 30 passing through holes 31 in the bar 5 secure the latter to the bed A. This is but one of many means of mechanical expediency for attaching our device, other means such as incorporating a hole in the 40 sides of the legs of the head end and inserting the ends of bar 5 therein by spring tensioning the same towards the center will as readily and satisfactorily serve the purpose.

In Figure 9, tabs 35 of flexible material 45 suitably secured to the shield 1 are attached to bed A by means of screws or similar means 36, the shield hanging free at the rear of the bed, and is brought to the front of the head panel by simply lifting up and letting hang from the top. In Figure 11, the brackets 3 are secured to the head end of the bed A at the front of the head end and somewhat below the pillow which serves to hide the entire device when not in use, a spring 55 roller 2 engaging the brackets, the shield 1 being attached to the roller at one end and to a bar 37 on the other, hooks 38 engaging said bar serving a means for hanging the shield from the top of the head end and thus 60 covering the front of the head end. As shown in Figure 13 the head end of the bedstead A has a recess or slot 43 formed therein, a concave paneled closure means 39 being shown to cover the same. Obviously, this closure 65 means may be of any other design and in

practice, it is manufactured to conform to the design and period type of the bedstead structure. The roller 2 having shield 1 attached is secured to said closure 39, the latter being in turn secured to the bed by means 70 of bolts 40 engaging the head panel and the ends 41 of the closure 39.

Various modifications of the bar structure may also be employed, for example, a rod 75 slidably positioned in a tube, said rod having a pin slidably engaging a slot in the tube and a groove sideways thereof as is common in the ordinary door bolt serving the purpose quite well.

As is apparent, the device in several types 80 is attached to the rear of the bedstead and in other types is attached directly to the front or to the top of the bed end, suitable attaching means other than disclosed being a matter of mechanical expediency. It is attached so 85 that no part thereof when not in service is in sight when observing the bed from either the front or side.

To place the several types attached to the rear of the bed into service, it is only necessary to reach with one hand behind and just below the uttermost top of the head end and grip the device. A gentle pull upwards (so easy that a child can do it) positions the device just above the top of the end, the sanitary shield in conformity with our method being thence brought upwards, forward and downward so as to cover the front area of the bed end.

To reposition out of the way, the reverse of 100 the foregoing need only be done, that is, the sanitary shield is brought upwards, backward, and downward, after which the device as a whole is pushed downwardly and from view.

In the respective types of our device shown in Figures 9 to 13 inclusive, the device is either placed directly on the top of bedstead end or directly in the front thereof, in either event, to place the sanitary shield in position for use 110 it is only necessary to draw the same downward or upward over the front paneling, the reverse being in order to place the same out of the way.

It is one of the basic characteristics of our 115 device irrespective of type and design, that it functions to cover the bedstead end regardless of the operating principle involved.

In size and shape, it is produced to conform to standard sized bedsteads in their 120 varying designs, and is adaptable for attachment to bedsteads of either metal or wood.

As a practical article of manufacture, it is 125 apparent that our device can readily be constructed of material obtainable in the open market and at a very negligible cost, thereby providing an article that should be acceptable to the masses regardless of means.

Conducive to the health of the individual 130 and the community at large, it should find a

responsive public, and it is safe to assume that students of health, and the health authorities in general will proclaim it a boon to mankind.

As many apparently widely different embodiments and changes in construction of this invention could readily be made without departing from the scope thereof as herein shown and described, it is intended that the description and drawings shall be interpreted 10 as illustrative and not in a limiting sense.

It is also to be understood that the language used throughout, inclusive of the claims, is intended to cover all of the generic and specific features of the invention, and all statements 15 of the scope thereof, which as a matter of language, might be said to fall therebetween.

Having thus described our invention, what we claim as new and novel, and desire to secure by Letters Patent, is:—

20 1. In combination with a bedstead, a bar, means by which the bar is secured to the bed end at the rear and below the top thereof, a second bar, means connecting the two bars so that the second mentioned bar may be retracted below the top of the bed end or extended above the top, a roller, means by which the roller is rotatably carried by the second mentioned bar and a flexible shield carried by the roller and adapted to be drawn off the 30 roller and extended over the front of the bed end.

25 2. In combination with a bedstead, a collapsible frame comprising a plurality of bars extensibly connected by pivoted link members, means for attaching one of said bars to one face of the bed end and below the top thereof, brackets on the ends of another of said bars, a roller having trunnions rotatably secured in slots in said brackets, a flexible shield rolled on said roller and adapted to be withdrawn and extended over the other face of the bed end when the second mentioned bar is extended.

30 3. In combination with a bedstead, a roller, means extensibly connecting the roller with one face of a bedstead end whereby the roller may be positioned behind and below the top of said end or supported above said end, a flexible shield detachably connected to and 45 rollable on said roller and adapted to be unrolled and spread over the other face of the bed end in either the retracted or extended position of said roller.

MARJORIE REQUA.

THOMAS LEE McCLELLAN.
